(57) **CLAIM**

The ornamental design for a shoe, as shown and described.

DESCRIPTION

1. Shoe

1.1 : Perspective

1.2 : Front

1.3 : Back

1.4 : Right

1.5 : Left

1.6 : Top

1.7 : Bottom

The design refers to a shoe; the representations show the shoe in a perspective view, a front view, a rear view, a right side view, a left side view, a top view and a bottom view, respectively; the various views of the design show only the right shoe; the left shoe is not shown as it is symmetrical to the right one; the shoe of the present design is shown in grey-scale, as protection of the present design is not to be limited to a specific colour and/or combination of colours of the shoe and of its parts.
